United States Patent Office

Des. 194,239
Patented Dec. 18, 1962

194,239

PUTTER HEAD

Robert W. Hyde, 1650 Colonial Drive, Cincinnati, Ohio

Filed Nov. 16, 1961, Ser. No. 67,561

Term of patent 14 years

(Cl. D34—5)

I claim:

The ornamental design for a putter head, substantially as shown.
